UNITED STATES PATENT OFFICE

ABE O. SAMUELS AND GEORGE ADAMS, OF ROCHESTER, NEW YORK; SAID ADAMS AS
SIGNOR TO SAID SAMUELS

KNIFE SHARPENER

Application filed August 16, 1928. Serial No. 300,040.

The invention relates to a knife sharpener, of the general type employing a plurality of overlapping rotatable sharpening disks between the intersection of the peripheries of 5 which a knife is drawn, and it has for its primary object to afford a simple construction that can be manufactured economically and is efficient in operation.

A further purpose of the invention is to 10 provide a structure requiring few parts which can be easily assembled and sold at a reasonable price.

Still an additional purpose of the invention is to afford a durable, sturdy construction 15 which can be readily operated and still give dependable service indefinitely.

To these ends, the invention consists in the form and arrangement of parts that will appear from the following description when 20 read in conjunction with the accompanying drawings, the novel features being pointed out in the claims following the specification.

In the drawings:

Figure 1 is a side elevation of a knife sharpener constructed in accordance with a preferred embodiment of the invention;

Figure 2 is a side elevation looking in the opposite direction from Figure 1, with the handle removed;

Figure 3 is a sectional view on line 3—3 of Figure 1;

Figure 4 is a sectional view on line 4—4 of Figure 2;

Figure 5 is a sectional view on line 5—5 of 35 Figure 2;

Figure 6 is a sectional view on line 6—6 of Figure 2, and

Figure 7 is a side elevation showing the application of the invention when used for 40 moving a bottle cap.

Referring more particularly to the drawings, in which like reference numerals refer to the same parts throughout the several views, the structure comprises a housing 45 consisting of two opposite walls preferably of sheet metal, which are circularly embossed, as indicated at 1 and 2, the edges of said walls being in juxtaposition, as shown at 3 and 4 respectively. The housing preferably has 50 the disk retaining pockets embossed therein,

although the housing may be otherwise formed with the edges of the opposite walls in contact and the main portions spaced from each other to afford disk retaining pockets.

5 and 6 designate two rotatable sharpening disks, preferably of metal, the inner edges of which overlap, as shown in Figures 1 and 3. The disk 5 is located in the embossed portion 2, the outer edge of the disk being retained between the inner surface of such embossed portion and the shoulder 7 on the opposite wall, while the outer edge of disk 6 is retained between the inner surface of the embossed portion 1 and the shoulder 8 on the opposite wall, as shown in Figure 3.

The side walls are cut away at 9, as shown in Figures 1 and 2 to afford a recess exposing the point of intersection between the disks and permitting access of a knife thereto, and adjacent said recess the walls are indented at 10 and 11 to prevent movement of the disks in that direction, the disks being thus held in cooperative relation entirely by the pockets of the housing cooperating with the peripheries of the disks and without any supporting means at the centers of the disks. The recesses 9 in the side walls of the housing are preferably of such form that the opposite edges of the housing bounding such recess may be used to remove a bottle cap in the manner shown in Figure 7.

The side walls of the housing also include angularly arranged shank portions, the outer ends of which lie adjacent to each other as indicated at 12. One of said shank portions is provided with an opening while the other has a correspondingly formed collar 13 engaging said opening to align the shank portions and prevent relative lateral movement thereof. Separation of the shank portions of the housing or walls is prevented when the structure is assembled, by means of the handle 14 which may be of any conventional form, the shank being driven into the handle as usual in this class of structure and as shown in Figure 1. The outer ends of the walls of the housing are held together by any suitable means, and in the construction shown such means consists of a rivet 15 engaging the outer surface of the housing 100

walls and passing through an opening 16 in the sharpening disk 5. It will be understood that the opening in the disk 5 is only to accommodate the rivet 15 which does not support the disk, the latter being held in place entirely by the form of the housing and its contact with its cooperating disk.

While the invention has been described with reference to a particular embodiment, it is not limited to the precise details herein disclosed, and this application is intended to cover such modifications or departures as may come within the intent of the improvement as herein set forth or the scope of the following claims.

We claim:

1. A knife sharpener comprising an elongated housing formed of opposite walls, each of said walls being circularly embossed to form two substantially circular disk retaining pockets and engaging each other at their edges around the outer peripheries of said pockets, a sharpening disk in each of said pockets, one arranged in contact with each of said walls and free from the other of said walls so that they overlap each other at their edges and are freely rotatable in said pockets, and indentations in said walls for retaining the disks in said pockets.
2. A knife sharpener comprising an elongated housing formed of opposite walls, each of said walls being circularly embossed to form two substantially circular disk retaining pockets and engaging each other at their edges around the outer peripheries of said pockets, a sharpening disk in each of said pockets, one arranged in contact with each of said walls and free from the other of said walls so that they overlap each other at their edges and are freely rotatable in said pockets, and means arranged in an enlarged opening in one of said disks for securing said walls to each other.

In witness whereof, we have hereunto signed our names.

ABE O. SAMUELS.
GEORGE ADAMS.
